UNITED STATES PATENT OFFICE.

CONRAD JOBST, OF TOLEDO, OHIO, ASSIGNOR, BY MESNE ASSIGNMENTS, TO THE TOLEDO AUTOMATIC BRUSH MACHINE COMPANY, OF TOLEDO, OHIO, A CORPORATION OF OHIO.

TUFT-FORMING MECHANISM.

Application filed January 7, 1922. Serial No. 527,589.

The invention relates to brush machines of that type in which the bristles for forming the tufts are automatically picked from the stock and are fed through a nozzle into engagement with the brush back. The present invention relates more particularly to the means for feeding the stock, and the cooperating parts by which the size of the tufts picked may be exactly predetermined and maintained constant throughout the operation. To this end the invention consists in the construction as hereinafter set forth.

Certain features of the brush machine described in the specification and illustrated in the drawings but not claimed herein form the subject matter of my co-pending applications, Serial No. 438,391, filed January 19, 1921, entitled Brush making machine; and Serial No. 527,590, filed January 7, 1922, entitled Brush machine.

In the drawings:

Figure 1 is a sectional side elevation of the stock-feeding mechanism and tuft-picking mechanism;

Figure 1^a is a fragmentary section of the mechanism for actuating the follower G;

Figure 1^b is a cross section on line 1^b—1^b of Figure 1;

Figure 2 is a sectional plan view thereof; Figures 3, 4 and 5 are sectional elevations showing the tuft picking needles and cooperating parts of the mechanism in different positions of adjustment;

Figure 6 is a vertical cross-section on line 6—6 of Figure 1;

Figure 7 is a horizontal section on line 7—7 of Figure 6;

Figure 8 is a perspective view of the tuft picking mechanism;

Figure 9 is a horizontal section on line 9—9 of Figure 3;

Figure 10 is a vertical cross-section on line 10—10 of Figure 2;

Figures 11 and 12 are respectively a sectional front elevation and a sectional plan view of portions of Figures 1 and 2.

In the forming of tufts for brushes it is very essential that these should be of uniform size and it is also important in the feeding of the bristles and the picking of the tufts to avoid any injury thereto. My improved mechanism is so constructed that the stock will be fed uniformly to the tuft picking mechanism and that full tufts of any

predetermined size can be successively picked without injury to the bristles. As shown, A is a stock holding receptacle which is preferably arranged in an inclined position with its lower end in operative relation to the picking mechanism. This receptacle consists of top and bottom bars A' A² and parallel side bars A³ A⁴ which are relatively adjustable to receive stock of different lengths. The adjustment of these side bars is preferably accomplished by mounting the same upon the transverse shafts B and C, projecting laterally from a bracket arm D, forming a part of the frame of the machine. The side plates are provided with apertured ears or lugs E slidably engaging the shafts B and C and adjustably secured thereon by set-screws F. Thus by loosening these set screws, the side plates may be adjusted nearer together or farther apart to accomodate the particular length of bristles being used.

The bristles are fed downward in the receptacle A by the pressure of a follower G having a shank G' passing outward through a housing H and being provided with a spring I sleeved thereon within said housing and abutting against the outer end thereof, the opposite end of said spring bearing against said follower. The follower G has bifurcated projections G² and G³ respectively embracing the top and bottom bars A' and A² of the receptacle. A handle I' at the outer end of the shank G' serves to retract the follower whenever it is desired to refill the receptacle.

To provide access to the receptacle, a portion A⁵ of its top wall is hinged at A⁶ and is normally held in position by a spring latch A⁷. When this latch is released, the member A⁵ may be turned up, permitting the insertion of the bristles and the filling of the receptacle therewith.

The picking mechanism comprises a pair of reciprocating needles J and K which are arranged centrally in front of the receptacle A and which grasp the tuft and carry it downward into alignment with the nozzle. The tuft is guided in its descent between the guides L and M, which are mounted upon the frame and are relatively adjustable as hereinafter described to increase or diminish the width of space therebetween. The needles slide in grooves L' and M' in the respective guides, the needle J having the

laterally extending hook J' beneath the tuft, while the needle K has the picking point K' and the laterally extending shoulder K^2 for bearing on the top of the tuft. Thus the two guides L and M and the portions J' and K^2 of the needles together surround the tuft and hold the bristles from displacement.

In the picking of the tuft the first essential is to bring the required number of bristles into engagement with the needles. It is obvious that the pressure of the follower G upon the stock in the receptacle A cannot be depended upon for delivering the required number of bristles to the picking needles. This is for the reason that the depth of the receptacle is many times the dimension of the tuft and as there is a considerable friction element between the bristles, they will not move or flow upon each other, as would be the case with a more plastic medium. I have therefore devised a mechanism by which an over-supply of bristles is first brought into proximity to the picking needles, after which the surplus bristles are forced back, leaving a full quantity for the tuft, the construction being as follows:

N is a member forming an inclined front for the receptacle A so as to produce a tapering or wedge-shaped space for the bristles. The member N is reciprocated longitudinally of the receptacle and in its forward movement permits the bristles under the actuation of the follower G to move bodily forward, while in the rearward movement of the member N the bristles in the wedge-shaped space are pressed downward and rearward. This will place upon the bristles at the point of the wedge-shaped space a pressure that is fully equal to that upon the body of the bristles between the walls A' A^2 . The lower end of the member N is preferably bent to form an acute angle with the bottom A^2 of the receptacle, as indicated at N' , and this acute angular space is occupied by the bristles from which the tuft is picked. It is, however, necessary to force the bristles into this space so as to completely fill the same, which is accomplished by a tooth O upon a member P that is periodically forced upward into the body of the bristles adjacent to the wedge-shaped space and is then moved forward to press the bristles into this space. As will be hereinafter described, the arrangement is such that subsequent to the forward movement of the member N , the tooth O will be operated to engage the bristles and force them forward, while upon the return movement of the member N , the tooth O will resiliently yield, permitting the bristles to be forced back, leaving the pocket completely filled but without injurious pressure upon the bristles.

The size of the tufts must be varied according to the particular brush to be manufactured and the bristles used therein. Pro-

vision is made for such adjustment (first) by forming one of the guides, such as the guide L , adjustable in relation to the co-operating guide M and (second) by varying the width of the wedge-shaped space between the portion N' of the member N and the bottom A^2 of the receptacle. The former adjustment is obtained by slidably mounting the guide L in ways Q on the frame and securing it by a clamping screw Q' . The adjustment of the member N' is preferably effected by slotting the end of said member at N^2 to engage a pin R , which is eccentrically carried on a rotatively adjustable pin R' . The pin R' may be rotated by a milled head R^2 and then clamped from displacement by the milled head set-screw R^3 .

The picking needles J and K are actuated by mechanism of the following construction: S is a guide-way for a pair of vertically reciprocating slides S' and S^2 and which respectively actuate the needles K and J . The slide S' is actuated by a bell crank lever T having a slotted bearing T' engaging a pin T^2 projecting outward from the slide S' through a slot S^4 in the guide S . The lever T rocks on the shaft T^3 projecting laterally from the bracket arm D . The slide S^2 is indirectly actuated from the lever T through the medium of the slide S' , but with a lost motion connection, permitting the initial independent movement of the slide S' . This lost-motion connection comprises a lug S^5 on the slide S^2 projecting into a recess in the slide S' and engaging a headed shank S^7 on which a spring S^6 is sleeved. The spring is of sufficient tension to hold the slide S^2 against movement during the initial downward movement of the slide S' until an adjustable pin S^8 on the slide S' contacts with the lug S^5 . Both slides will then move together to complete their downward movement and will remain together during their return or upward movement until the upper end of the slide S^2 contacts with an adjustable stop S^9 , which arrests further movement. The slide S' will, however, continue to move upward, this being permitted by the compression of the spring S^6 .

The needle K is rigidly connected to the slide S' , but the needle J is pivotally connected to the slide S^2 by the pin J^2 . Above the pin J^2 the needle is provided with a laterally-extending portion J^3 , which in the downward movement of the slide comes in contact with a stationary cam J^4 , thereby rocking the needle on its pivot and moving the hooked end J' laterally away from the needle K . J^5 is a spring interposed between the needle J and the slide S^2 to yieldingly hold the needles together and J^6 is a screw carried by the slide forming an adjustable stop for the laterally extending portion J^3 of the needle. The construction is such that in

the initial movement of the slide S' , the needle K only is actuated, while the needle J remains stationary in a position for receiving the tuft. The descent of the needle K will cause the point K' thereof to be inserted between the bristles forming the tuft and the bristles adjacent thereto, and after such separation, both needles K and J will move together downward, carrying the tuft between the guides L and M . This continues until the portion J^3 of the needle J engages the cam J^4 , whereupon the hooked portion J' is laterally withdrawn from the path of the tuft and remains thus withdrawn by the cam J^4 . In this manner the tuft is disengaged from the needle J and is not disturbed during the return movement of both needles. The tuft thus conveyed to the lower end of the guides L and M is then engaged by the tuft-setting mechanism as indicated at Z but as this forms no part of the present invention, all description thereof will be omitted.

In the complete brush machine, of which the mechanism thus far described forms a part, the various units are co-related and timed in their relative movements. Thus the member P is preferably actuated by and timed with the tuft-setting mechanism, but so far as the present invention is concerned, it could be operated from any other part of the driving mechanism, which is properly timed. As shown, the member P is pivotally mounted on a pin U which projects laterally from a slide U' longitudinally slidable in guides U^2 . This slide is intermittently actuated from a second slide U^3 , which is reciprocated by a link U^4 connected to a pitman rod U^5 engaging a crank U^6 on the main drive shaft of the brush machine. The slide U^3 carries the spaced spring pressed bumpers U^7 and U^8 and these alternately engage with a depending finger U^9 on the slide U' . The arrangement is such that at one end of the reciprocating movement of the slide U^3 , the bumper U^8 will strike the finger U^9 and actuate it in one direction, while at the opposite end of the reciprocating movement of said slide U^3 , the bumper U^7 will strike the finger U^9 and actuate it in the opposite direction. The slide U' has connected thereto the threaded shank V which passes through an aperture in a stop pin V' and has adjustable nuts V^2 thereon by means of which the amount of movement imparted to the slide U' can be limited. The tooth O is yieldably connected to the member P through the medium of a shank P' and a spring P^2 . There is also provided means for raising and lowering the tooth O , comprising an arm P^3 which engages a cam face P^4 on the slide U^3 . Thus, where such slide is moved to the left, Figs. 1 and 11, the cam P^4 , by engaging the arm P^3 , will rock upward the arm P and press the tooth O into the bristles in advance of the movement of the slide U' by actuation of the bumper U^8 , while in the return movement of the slide U^3 the tooth O will be depressed out of engagement with the bristles in advance of engagement of the bumper U^7 with the finger U^9 to actuate the slide U' in the reverse direction.

The member N is actuated by any suitable connection, properly timed, but, as shown, the rear end of said member is connected with a lever X , which frictionally engages a bearing Y on the frame. The opposite end of said lever X is connected by a link X' having an adjustable portion X^2 with a pin X^3 on the bell crank lever T . Lost motion is provided by a slot X^4 in the link X' , so that said link is only intermittently actuated by the lever T near the opposite ends of the reciprocating movement thereof. Adjustable stops Y^2 and Y^3 , respectively on the member N and the link X' , will determine the exact degree of movement imparted to the member N .

In operation, the bristles are first placed in the receptacle A by turning up the hinged cover A^3 and withdrawing the follower G through the actuation of the handle I' . After the filling of the receptacle, the cover A' is turned down and engaged with the latch A^7 and the follower G is released to be under the resilient pressure of the spring I . Motion is imparted to the mechanism from the main shaft through the crank U^6 , pitman U^5 , link U^4 and bell crank T . The latter actuates the needles J and K , as has been before described, and also actuates the member N and slides U^3 , the sequence of operations being as follows:

When the needles J and K approach the lower end of their movement, the member N is actuated by the pin X^3 , link X' and lever X so as to be moved forward and because of the engagement of pin R with the inclined slot N^2 , the member N is moved slightly upwardly as well as forwardly to enlarge the wedge-shaped space. This permits the bristles to feed forward under the action of the spring pressed follower G . At the same time the slide U^3 , being at the rearward end (towards the right in Fig. 1) of its movement, withdraws the cam P^4 from the arm P^3 , dropping the arm P and tooth O out of engagement with the bristles. During the upward movement of the needles J and K , the cam P^4 on the slide U^3 engaging the arm P^3 will raise the same and the arm P and tooth O , pressing the latter upward into the body of bristles. When the needle J has reached the limit of its upward movement and the needle K has been raised above the wedge-shaped space in the magazine, the striking of the bumper U^8 against the finger U^9 will actuate the slide U' and thereby the arm P and tooth O , so that this tooth will press the bristles forward (to the left) into the wedge-

shaped space. Simultaneously or following this movement the pin X^3 , having completed its lost motion in the slot X^4 , will actuate the link X' , lever X and member N , moving the latter rearward (to the right), contracting the wedge-shaped space and compacting the bristles against the tooth O . However, the latter is yieldable by reason of the spring P^2 so that this pressure cannot be enough to injure the bristles, but will merely completely fill the space. Thus in the succeeding downward movement of the needle K , the point thereof will be inserted between the compacted bristles in the wedge-shaped space and will separate the required number for the tuft from the mass. These will be carried downward and delivered to the tuft-setting mechanism (not shown).

Where it is desired to enlarge or diminish the size of the tuft, the wedge-shaped space can be changed by adjustment of the eccentric pin R and thereby raising or lowering the member N . This member, as shown in Figure 8, is bifurcated having the slot N^3 through which the needles J and K pass, and the furcations also embrace an upwardly extending portion L^2 of an adjustable guide block L^3 , forming the guide-way L . Thus by also adjusting this block L^3 , the distance between the guide-ways L and M may be varied to correspond to the size of the tuft which is picked.

By reason of the fact that the bell crank lever T is actuated from the crank U^6 through the medium of the pitman U^5 and link U^4 , there is imparted thereto a substantially harmonic movement and a similar movement to the needles J and K . This is important as it permits of picking the tuft and depositing the same during the slow velocity portions of the cycle, while the transportation of the tuft is accomplished during the high velocity portion of the cycle. It is therefore possible to drive the machine at a higher rate of speed than could be safely used if the velocity of the needles and associated parts was uniform.

What I claim as my invention is:

1. In a brush machine, a magazine for the bristles having a longitudinally extending wall and a movable wall inclined thereto forming a tapering end portion, a yieldably pressed follower for feeding the bristles toward the tapering end portion, and means for oscillating said inclined wall in a direction longitudinally of said magazine to effect alternate expansion and compression of the bristles whereby the feeding of the same into the tapering portion is facilitated.
2. In a brush machine, an elongated magazine for the bristles having a pair of non-parallel walls forming a progressively expanding chamber, a movable wall inclined toward one of said non-parallel walls and forming therewith a progressively contract-

ing tapering end portion, a yieldably pressed follower for feeding the bristles in the direction of expansion of said chamber and towards the tapering end portion, and means for oscillating said movable wall longitudinally of said magazine in the general direction of feeding pressure to facilitate the movement of the bristles towards the apex of said tapering end portion.

3. In a brush machine, the combination with a pair of cooperating vertically reciprocating tuft picking needles, of an elongated magazine for the bristle stock having a bottom wall inclined with respect to said reciprocating needles, a top wall non-parallel to said bottom wall forming an expanding chamber therebetween, a movable end wall inclined at an acute angle to said bottom wall and forming therebetween a tapering chamber, the apex of which crosses the path of said picking needles, side walls adjustable to receive bristles of different lengths, a follower for feeding the bristles in the magazine toward the tapering end wall thereof, and means for oscillating said movable end wall longitudinally of said magazine to facilitate the movement of the bristles into the apex of the tapering chamber.

4. In a brush machine, the combination with a pair of cooperating vertically reciprocating tuft picking needles, of an elongated bristle magazine having a bottom wall, an end wall inclined at an acute angle with said bottom wall forming a tapering chamber having the apex crossing the path of said picking needles, means for feeding the bristles in said magazine towards said tapering chamber, means for oscillating said movable wall longitudinally of the bristle magazine to alternately expand and compress the bristles and to facilitate the movement of the same towards the apex, means for engaging the bristles at the apex of said chamber and for pushing the same forward during the forward phase of the oscillating movement of said movable wall, said pushing means yieldably opposing the return oscillation of said movable wall to compact the bristles in the apex of the chamber.

5. In a brush machine, the combination with a pair of cooperating reciprocating tuft picking needles, of an elongated magazine having a wall arranged transverse to said tuft picking needles, a movable end wall inclined in acute angular relation to the first mentioned wall forming a tapering chamber with the apex thereof crossing the path of said needles, means for intermittently reciprocating said movable end wall longitudinally of said magazine in timed relation to the reciprocation of said needles, means for adjusting said movable end wall to enlarge or contract the portion of the chamber crossing the path of the needles, and means for corre-

spondingly adjusting said needles to enlarge or contract the size of the tuft to be picked.

6. In a brush machine, the combination with a pair of cooperating reciprocating tuft

5 picking needles, of a bristle magazine having a tapering outlet with the apex thereof crossing the path of said needles, means for adjusting said magazine in a direction transverse to the reciprocation of said needles to 10 enlarge or contract the distance that the outlet extends across the path of the needles, and means operable within the apex of said outlet for exerting a localized pressure on the bristles therein to uniformly compact the 15 same whereby the size of the tufts picked is determined by the adjustment of said outlet.

7. In a brush machine, a tuft picking mechanism comprising a reciprocatory needle, means for positively actuating the same, 20 a cooperating needle, a lost motion drive connection between said positively actuated needle and said cooperating needle for positively

25 and directly actuating the latter from the former in one direction of its movement, means for yieldingly driving said cooperating needle from said positively actuated needle in the reverse direction, and a stop for arresting movement of said cooperating needle to permit separation of the same from 30 said first mentioned needle for the gathering of the tuft.

8. In a brush machine, a tuft picking mechanism comprising a pair of cooperating needles, means for positively actuating one 35 of said needles with a simple harmonic motion, means on the other of said needles for directly engaging the first mentioned needle whereby the second needle is driven directly from the first needle in one direction of

40 movement, a yieldable resilient connection between said positively actuated needle and the cooperating needle for driving the latter in the reverse direction and permitting a relative movement of said needles in said reverse direction, and a stop for arresting movement of said cooperating needle prior to the completion of one phase of the reciprocation of said first mentioned needle to 45 separate said needles for the gathering of the tuft during a low velocity portion of the harmonic cycle.

9. In a brush machine, the combination with a pair of cooperating reciprocating tuft picking needles, of a magazine forming a tapering chamber with the apex thereof crossing the path of said picking needles, means for oscillating one wall of said tapering chamber to alternately expand and compress the bristles therein and to facilitate the feeding of the same towards the apex, a feeding tooth intermittently inserted into the bristles adjacent to the apex of said chamber, and means for yieldably pressing said feeding tooth in a direction towards the apex of said 55 chamber in opposition to the return phase of

the oscillatory movement of said wall of the magazine, whereby the bristles from which the tuft is picked are uniformly compressed.

10. In a brush machine, the combination with a pair of cooperating reciprocating tuft 70 picking needles, of a bristle magazine having an end portion thereof in acute angular relation to the bottom portion forming a tapering chamber with the apex crossing the path of said needles, means for feeding the 75 bristles in said magazine towards the tapering portion thereof, means for oscillating said end portion to alternately expand and compress the bristles and to facilitate the feeding of the same into the apex, means for adjusting said oscillating end portion to enlarge or diminish the area traversed by the needles, and means for yieldably opposing the return of the bristles in the apex 80 of said chamber to place a uniform compression on the portion from which the tuft is picked.

11. In a brush machine, a tuft picking mechanism comprising a pair of cooperating reciprocatory picking needles, a bristle 85 magazine having a tapering outlet with the apex thereof extending across the path of the picking needles, means timed with the movement of the picking needles for alternately expanding and contracting the outlet 90 of said magazine crossed by the picking needles, and means operable in said outlet for yieldably resisting the inward movement of the bristles during the contracting of said outlet to place upon the bristles from which 95 the tuft is picked a uniform pressure.

12. In a brush machine, a tuft picking mechanism comprising a picking needle, a cooperating hooked needle, means for reciprocating said needles with a substantially 100 harmonic movement between the points for gathering and delivering the tuft, means for arresting movement of the hook-shaped needle at the gathering point to permit separation therefrom of the picking needle to 105 receive the tuft, and means for laterally withdrawing said hook-shaped needle at the point of delivering the tuft to permit the return of said needles.

13. In a brush machine, a tuft picking 115 mechanism comprising a picking needle having a clamping shoulder adjacent its end, a cooperating hook-shaped needle constituting an opposed shoulder, a pair of parallel reciprocatory slides to which said needles are 120 respectively attached, means for positively actuating the slide of the picking needle with a substantially harmonic movement, a resilient yieldable connection between said slide and the slide for the cooperating needle, means for arresting the latter slide to permit separation of the picking needle from the hook-shaped needle for the gathering of the tuft, and adjustable means for limiting 125 the relative movement of said picking needle 130

and cooperating needle to enlarge or diminish the space between the clamping shoulders.

14. In a brush machine, a tuft picking mechanism comprising a picking needle, a cooperating hook-shaped needle, a pair of parallelly arranged slides to which said needles are respectively attached, means for imparting to the slide of the picking needle a positive substantially harmonic movement to carry said needle from the gathering point to the point of delivery, a yieldable resilient connection between said slide and the second slide, means for arresting movement of the latter slide prior to the completion of one phase of the harmonic cycle to separate said needles for the gathering of the tuft, and means operating adjacent to the completion of the opposite phase of the harmonic cycle for laterally withdrawing said hook-shaped needle to be disengaged from the tuft during the return movement thereof.

15. In a brush machine, a tuft picking mechanism comprising a guide-way, a pair of slides reciprocating in said guide-way, means for imparting to one of said slides a positive and substantially harmonic movement, a yieldable resilient connection between said slide and the other slide, means for arresting movement of the latter slide prior to the completion of one phase of the harmonic movement, a picking needle rigidly attached to said first-mentioned slide, a cooperating hook-shaped needle pivotally attached to the other slide, means for yieldably holding said needles adjacent to each other during the period of gathering the tuft and transporting of the same in the opposite phase of the harmonic movement, and means for tilting said pivotal needle prior to the completion of the transporting movement to disengage the hook from the tuft for return movement.

16. In a brush machine, a tuft picking mechanism comprising a guide-way, a pair of parallel reciprocating slides therein, means for imparting to one of said slides a positive and substantially harmonic movement, a yieldable resilient connection between said slide and the other slide, a stop for arresting the latter slide before the completion of one phase of the harmonic movement, an adjustable stop for altering the lost motion permitted between said slides, a picking needle carried by the positively actuated slide and having a clamping shoulder adjacent to the picking point, a cooperating hook-shaped needle pivotally attached to the other slide, the distance between said hook and shoulder being altered by adjustment of said stop between slides, means for resiliently and yieldably holding said needles adjacent to each other during the greater part of the cycle, and a cam operating on said pivoted needle prior to the completion

of the opposite phase of its harmonic movement for tilting said needle and laterally withdrawing the hook.

17. In a brush machine, a tuft picking mechanism comprising a pair of cooperating reciprocating picking needles, a bristle magazine having a portion extending across the path of the needles, means for enlarging the space extending across said needles in transverse directions, a yieldable follower 75 for pressing the bristles in one direction into said enlarged space, and means for contracting said space in transverse directions against the yielding pressure of said follower to uniformly compress the bristles 80 from which the tuft is picked.

18. In a brush machine, a tuft picking mechanism comprising a pair of cooperating reciprocating picking needles, means for separating said needles at one point in their reciprocation for receiving the bristles for a tuft, a bristle magazine having a portion extending across the path of said picking needles, means operating during the interval in which said needles are separated for enlarging the space in said magazine which extends across the path of the needles, and a yieldable follower for pressing the bristles into said enlarged space in one direction of enlargement, said means for enlarging said space also operating prior to the picking of the tuft for contracting said space against the yielding pressure of said follower to uniformly compact the bristles from which the tuft is picked. 95

19. In a brush machine, a tuft picking mechanism comprising a pair of cooperating reciprocating picking needles, means for imparting to said needles a substantially harmonic movement, means for effecting a separation of the needles to receive the tuft during the low velocity period of the harmonic movement, a magazine having a portion thereof extending across the path of the needles, means for enlarging said portion of the magazine in transverse directions during the period in which the needles are separated, and subsequently contracting said space in said transverse directions while the needles are still separated, and a follower 110 for pressing the bristles into the space in one direction of enlargement thereof and for yieldably resisting the opposite movement of said bristles during the contraction of the space, whereby uniform density is obtained 115 in the portion of the bristles from which the tuft is picked. 120

20. In a brush machine, a tuft picking mechanism comprising a bristle magazine, 125 a pair of cooperating tuft picking needles reciprocating between said magazine and a point for depositing the tuft, means for imparting to one of said needles a positive and substantially harmonic movement, a yield- 130

- able resilient connection between said needle and the cooperating needle for driving the latter from the former, a stop for arresting movement of the cooperating needle when in registration with the magazine to permit the separation of said needles for the receiving of the tuft, means for enlarging in transverse directions the space in said magazine which lies across the path of said needles, a follower operating to press the bristles in one direction of enlargement of said space, said follower yieldably opposing the contraction of the space and thereby securing uniform density to the bristles from which the tuft is picked.
21. In a brush machine, the combination with a pair of cooperating reciprocating tuft picking needles, of a guide-way along which the tuft is transferred by said needles during the reciprocating movement thereof, a magazine for the bristles having a portion of its space extending across the path of the needles, an oscillatory member forming an end portion of said magazine and also a portion of said guide adapted upon the oscillation thereof to alternately enlarge and contract the space which is in the path of the needles, a follower for pressing the bristles in one direction into said enlarging space

and yieldably resisting the compression of 30 said space, and means for adjusting said oscillatory member for enlarging or diminishing said guide-way and the space from which the tuft is picked to permit of altering the size of tufts.

22. In a brush machine, the combination with a pair of cooperating vertically reciprocating tuft picking needles, of a magazine having an inclined bottom extending adjacent to said needles, a vertical guide at 40 the end of said bottom, a member having a portion extending in acute angular relation to said bottom, forming a tapering space in said magazine which extends across the path of the needles, a guide-way secured to said 45 last-mentioned member and opposed to said first-mentioned guide, means for oscillating said member to alternately enlarge and diminish the space in the magazine which extends across the path of the needles, and 50 means for adjusting the limits of oscillation of said oscillatory member to enlarge or diminish the space from which the tuft is picked during the interval in which the picking occurs.

In testimony whereof I affix my signature.

CONRAD JOBST.
